CLAMPING MEANS

Christopher L. Hardwick, Cleveland, Tenn.

Application September 27, 1945, Serial No. 618,918

2 Claims. (Cl. 248—361.)

1

This invention relates to a clamping means particularly adaptable for securing together the burner and grid assembly of a cooking stove to obviate the danger of these elements being damaged during shipment.

The principal object of the present invention is the provision of a clamping means for binding together the top burner grids, burner housings and top burners of a cooking stove to obviate the danger of these loosely mounted and normally disconnected elements being displaced and damaged during shipment.

Another object is the provision of a relatively simple and inexpensive clamping means which is readily adapted for assembly and disassembly with respect to the top heating elements of a stove prior to and after shipment respectively.

A further object is to provide a clamping means for securing together the burner and grid assembly of a stove during shipment and which is provided with a cushioning means for protecting these elements.

These and other objects and advantages will be apparent as the specification is considered in connection with the accompanying drawings, wherein:

Figure 1 is a plan view of a portion of a cooking stove, showing the relative positions of the clamping devices, grids, burner housings and burners;

Figure 2 is a section through one of the burner assemblies of Figure 1, showing one of the clamping devices in operative position relative to the grid, burner housing and burner;

Figure 3 is a perspective view of one of the clamping devices, prior to being secured in place on the grid and burner assembly; and

Figure 4 is a bottom plan on one of the burners showing the hooked shank of the clamp in clamping position.

Referring more particularly to the drawings, wherein similar reference characters refer to like parts throughout the several views, 1 designates the cooking top of a stove or range, only a portion of the top of which is shown. A pair of conventional spaced annular burners 2 are suitably mounted in a substantially rectangular relatively shallow burner space or compartment 3, provided beneath the top 1 of the stove for this purpose. Each burner comprises a body portion 4 and a removable top portion 5, fuel being supplied to the inlet ends of integral mixing tubes 6, from a suitable source of gas supply, not shown. It is common practice to form the body of such burners with a relatively narrow integral cross

2

web 7 for supporting an upstanding threaded post 8, and it is also old to provide the removable burner top or cap 5 with a similar cross web 27. The latter web is provided with a threaded aperture 9 adapted to receive the threaded post 8 when the burner cap is screwed home against the burner body.

Access is had to the burner compartment 3 through a rectangular opening 10 formed in the stove top 1. The sheet metal top is bent downwardly and thence inwardly to form vertical flanges and horizontal flanges 11 and 12, respectively, about the opening 10. A recess is thus formed in which a burner plate 13 seats flush with the stove top. This burner plate is depressed to form annular drip flanges 14, surrounding spaced circular openings 15, through which the tops of the annular burners 2 slightly protrude.

20 Mounted on the top of the burner plate 13, and extending over the circular burner openings 15, in the substantially horizontally disposed annular flanges 14, are a pair of spaced cooking grates or grids 16 having four radially extending

15 legs 26 which rest on the upper face of the burner plate. As the grids are rather loosely mounted

25 on the burner plate and the latter are freely seated in the rectangular opening 10, these elements are adapted to be readily assembled and disassembled for cleaning and servicing purposes. This is desirable in the interest of simplicity and cheapness of manufacture and is the generally accepted practice with stove manufacturers. However, as the grids and burner plate are freely

30 mounted on the stove top, it is apparent that some means must be employed to clamp these elements to the stove to prevent the same or the stove being damaged during shipment. It is particularly desirable that such clamping means

35 be reused from time to time to thereby reduce and minimize the overall shipping costs, in addition to securely clamping the stove elements together and protecting the same during shipment.

40 As it will be understood that a clamping assembly 45 is employed for each burner unit a description of one assembly will suffice.

My improved clamping assembly comprises a metal bolt 17 having the threaded portion 18 at its upper end and being formed with a curved, bent or arcuately shaped hook 19 at its lower end. The bolt is of sufficient length to permit of its being inserted through a central opening 20 in the annular burner 2 so that the bent hook 19 thereof will fit around the integral cross web 7 extending across the body 4 of the burner 2, as

best shown in Figures 2 and 4. The shank of the bolt projects through the burner opening beyond the corresponding integral cross web 27 extending across the removable burner top or cap 5, and the upper threaded end of the bolt extends above the top plane of the grid 16. By reference to Figure 2, it will be noted that hook portion 19 of bolt 17 being centrally arranged engages with the centrally located bottom cross web 7, of the burner body 4, whereas the shank of the bolt is slightly offset from and extends parallel to the vertical axis of the burner and to one side of the cross web 27.

Sleeved over the shank of the bolt is a relatively large piece of heavy corrugated cardboard 21. While I have shown this piece as being somewhat square or rectangularly shaped, it will be apparent that it may be circular or of any desired shape. The cardboard strip 21 is of sufficient size that it will flatly engage with the sloping top face 22 of the burner top 5. A relatively thin metal disk or washer 23 is formed with a central aperture 24 through which the shank of the bolt 17 extends whereby the disk flatly engages the top face of the cardboard piece 21. A nut 25 mounted on the threaded bolt shank is adapted when appropriately rotated, to press the disk 23 and adjacent cardboard strip 21 flatly and tightly against the burner top 5, in an obvious manner. A corresponding although somewhat larger strip or piece 28 of heavy corrugated cardboard is sleeved over the upper end of the bolt shank and rests upon the grate 16, and a relatively thin metal disk 29 formed with a central aperture 24' is sleeved upon the upper portion of the bolt 17 and engages with the cardboard 28. A pair of nuts 30 threadedly engaging the threaded shank of bolt 17 are adapted to force the disk 29 downwardly against the cardboard strip 28 and press the latter tightly against the grid 16, as illustrated in Figure 2. Thus the grid 16 will be forced downwardly against the burner plate 13 and clamp the latter in its seat within the stove top 1. At the same time the burner is maintained in relatively immovable position with respect to the grates and other parts of the stove.

From the foregoing it will be understood that the clamp assemblies firmly and securely clamp together the burners, burner castings and grids and prevent the same from becoming displaced and thereby damaged during shipment. The clamps may readily be disassembled, in an obvious manner, by successively removing the nuts 30 and 25, disks 29 and 23, and upper and lower cardboard strips 28 and 21 and thereby permitting of the assemblies being reused. The cardboard pieces 21 and 28 in addition to insuring a

resilient clamping action serve to protect the porcelain finish of the stove.

While I have shown a preferred embodiment of my clamping assembly, it is to be understood that various changes and modifications may be made without departing from the scope and spirit of the appended claims.

Having thus described my invention:

What I claim is:

1. A clamping means for securing together upper and lower and intermediate superposed parts, said intermediate and lower parts each having an upper and a lower cross web respectively, said cross webs being of substantially the same width and in vertical alinement with each other, said clamping means comprising a threaded shanked member, hook-shaped means on the lower end of the shank of said shanked member removably engageable beneath said lower cross web and the intermediate portion of said shanked member above said hook-shaped means adapted to extend above and adjacent to one side of said upper cross web, a pair of spaced apertured clamping members, said apertures being offset from but in substantial alinement with one side face of each of said cross webs, said clamping members adapted to be loosely mounted on said threaded shanked member, and nuts co-operating with said apertures and threadedly mounted on the upper end of said shanked member engageable with the upper faces of said clamping members for forcing said clamping members against said upper and intermediate parts respectively whereby said upper, lower and intermediate parts will be clamped together.

2. A claim according to claim 1 wherein cushioning means is interposed between the respective clamping members and the said upper and intermediate parts.

CHRISTOPHER L. HARDWICK.
